UNITED STATES PATENT OFFICE.

ELMER L. ALDRICH AND LOUIS D. GIBSON, OF NORWAY, MAINE, ASSIGNEES TO THE
W. F. TUBBS COMPANY, OF NORWAY, MAINE, A CORPORATION OF MAINE.

DESIGN FOR A CHAIR.

Application filed October 11, 1928. Serial No. 28,466. Term of patent 14 years.

To all whom it may concern:

Be it known that we, ELMER L. ALDRICH and LOUIS D. GIBSON, citizens of the United States, residing at Norway, in the county of Oxford and State of Maine, have invented a new, original, and ornamental Design for Chairs, of which the following is a specification, reference being had to the accompanying drawing, forming part thereof.

The figure is a perspective view of a chair, showing my new design.

We claim:

The ornamental design for a chair, as shown.

ELMER L. ALDRICH.
LOUIS D. GIBSON.
